FIG. 1.

FIG. 2.

FIG. 1 is a top plan view of a curtain fabric showing my new design, the design unit being repeated in regular succession as indicated, the curtain fabric is shown broken away for the convenience of illustration. FIG. 1 shows approximately one-third of the total width of the fabric, the center portion being plain and unornamental and the portion adjoining the opposite selvage being identical to that shown.

FIG. 2 is an enlarged fragmentary top plan view of the flower detail of the curtain fabric of FIG. 1.

I claim:

The ornamental design for a curtain fabric, substantially as shown and described.
